UNITED STATES PATENT OFFICE

ROY RALSTON RINGER, OF PITTSBURG, PENNSYLVANIA.

TOOTH-BRUSH.

No. 901,835.

Specification of Letters Patent.

Patented Oct. 20, 1908.

Application filed March 28, 1907. Serial No. 365,064.

To all whom it may concern:

Be it known that I, ROY RALSTON RINGER, a citizen of the United States of America, residing at Pittsburg, in the county of Allegheny and State of Pennsylvania, have invented certain new and useful Improvements in Tooth-Brushes, of which the following is a specification, reference being had therein to the accompanying drawing.

10 This invention relates to tooth brushes, and the invention has for one of its objects to provide a brush having a novel construction of handle in which tooth powder or paste can be placed.

15 Another object of this invention is to provide a simple and inexpensive tooth brush that will enable powder and paste receptacles to be dispensed with, and provide a new article of this character adapted to be disjointed 20 and thus particularly adapted for travelers.

With the above and other objects in view, the invention consists in the novel construction, combination and arrangement of parts to be hereinafter more fully described and 25 then specifically pointed out in the appended claims.

Referring to the drawing forming part of this specification, like numerals of reference designate corresponding parts throughout 30 the several views, in which:—

Figure 1 is a view in elevation of a tooth brush constructed in accordance with my invention, Fig. 2 is a plan view of the same partly in longitudinal section, showing the 35 parts disconnected.

The improved device comprises a tubular handle 3, preferably tapered as shown in Figs. 1 and 2, and internally threaded at the smaller end and reduced in size at the larger 40 end with the reduced portion externally threaded as at 8, the reducing of the handle at the larger end producing a shoulder at the inner end of the externally threaded portion. The reduced externally threaded portion is 45 designed to receive a cap 6 internally threaded as at 7 to engage the threads 8, the inner edge of the cap bearing against the shoulder at the reduced end of the handle.

The bristle receiving portion of the brush

is represented at 1 and is formed with its inner end internally threaded to correspond with the internally threaded smaller end of the handle, the internally threaded portions adapted to receive a threaded plug 5, whereby the two parts 1 and 3 are firmly coupled, 55 while at the same time they are readily detachable when required.

The plug 5 may be employed as a closure to the smaller end of the handle when the bristle portion 1 is detached. The tubular 60 handle may be utilized for holding the powder or paste which will remain therein when the bristle holding portion 1 is detached with the plug remaining in the handle 3. An implement thus constructed is of great convenience and utility, especially for travelers, as it obviates the necessity of carrying a separate receptacle for tooth powder or paste, while at the same time the brush can be disjointed to enable it to occupy less space in 70 length than an ordinary brush.

Throughout my invention I construct the parts thereof to snugly fit together and thereby providing a smooth exterior surface similar to the ordinary tooth brush.

75 My improved tooth brush can be constructed of any desired material, the bristle holder being preferably of ivory or composition, while the handle thereof is preferably of metal or a composition.

80 What I claim and desire to secure by Letters Patent, is:—

A tooth brush comprising a tubular handle internally threaded at one end and provided with a detachable cap at the other end, a 85 bristle holding member internally threaded at the inner end, and a threaded plug engaging the internally threaded portion of the bristle holding member and the internally threaded portion of the handle and forming 90 a detachable coupling means between the parts.

In testimony whereof I affix my signature in the presence of two witnesses.

ROY RALSTON RINGER.
